United States Patent [19]
Kawamura

[11] Patent Number: Des. 293,654
[45] Date of Patent: ** Jan. 12, 1988

[54] ELECTRONIC THERMOMETER

[75] Inventor: Masaki Kawamura, Osaka, Japan

[73] Assignee: Sharp Corporation, Osaka, Japan

[**] Term: 14 Years

[21] Appl. No.: 742,104

[22] Filed: Jun. 5, 1985

[30] Foreign Application Priority Data

Dec. 6, 1984 [JP] Japan 59-50490

[57] CLAIM

The ornamental design for an electronic thermometer,
as shown and described.

DESCRIPTION

FIG. 1 is a top plan view of an electronic thermometer
showing my new design;

FIG. 2 is a bottom plan view thereof;

FIG. 3 is a front elevational view thereof;

FIG. 4 is a rear elevational view thereof;

FIG. 5 is a right side elevational view thereof; and

FIG. 6 is a left side elevational view thereof.

FIG. 1

FIG. 2

FIG. 3

FIG. 4

FIG. 5

FIG. 6
